[57] **ABSTRACT**

A reversible wrench with a ratchet and pawl mounted in respective apertures of a one-piece head and held in the head by a common retaining member. In one form, the head has a movable handle attached to it, the position of the handle relative to the head determining the ratchet drive direction, the handle being provided with an extension which acts as the common retaining member and holds the ratchet and pawl within the head regardless of handle position.

REVERSIBLE RATCHET WRENCH WITH INTERLOCKED ASSEMBLY

BACKGROUND OF THE INVENTION

1. Field of the Invention

The invention disclosed herein relates to reversible ratchet wrenches, and more particularly to those having movable handles (or movable members in the handles) for determining the drive direction of the ratchet.

2. Description of the Prior Art

Reversible ratchet wrenches have long been known. According to this prior art, the ratchet and pawl members have been retained in the head by means of covers held in place by several screws, and reversal of the drive direction of the ratchet has been determined by the setting of control members located on the head or in the handle. These wrenches have been generally satisfactory, but require a multiplicity of parts. Further, the screws tend to come loose, often allowing the cover to float such that the operative relation between ratchet and pawl is affected detrimentally.

SUMMARY OF THE INVENTION

It is an object of the invention to provide an improved ratchet wrench having a smaller number of parts because some serve a dual function.

It is another object of the invention to provide a ratchet wrench having a one-piece body containing a ratchet, a pawl, and a common retainer for holding both ratchet and pawl in the one-piece body.

It is still another object of the invention to provide a ratchet wrench which has a one-piece body into which can be inserted a ratchet, a pawl, and a handle, the insertion of the handle to a detented position serving to lock the assembly together.

The invention basically is a reversible ratchet wrench of the type having ratchet and pawl members, the wrench comprising a one-piece body having openings in which the ratchet and pawl members are disposed in reversible driving engagement, the ratchet and pawl members being held in the body by common interaction with a retainer inserted within the one-piece body.

DESCRIPTION OF THE PREFERRED EMBODIMENTS

FIG. 1 shows a first embodiment of an improved ratchet wrench 10, which is intended primarily for snap-on tools, such

as socket wrenches, although it could also be used as a threading die wrench or other tool driver. The improved wrench 10, according to the first embodiment, comprises a one-piece body 14, hereinafter referred to as head 14, and a handle 12 inserted within head 14, the handle being rotatable with respect to its longitudinal axis for purposes of drive-direction control of tool driver 16, as will be described. As shown in FIG. 1, a double-tooth pawl member 18 engages a circular ratchet 13 forming part of the tool driver 16. In the position shown in FIG. 1, the handle 12 is so oriented that it urges the upper one of the two teeth 15 on pawl 18 such that it falls between the teeth of ratchet 13. In the position shown, pawl tooth 15 is in locking engagement with ratchet 13 for counterclockwise rotation of head 14, but in yieldable engagement with respect to clockwise rotation of head 14.

Engagement is controlled by means of a plunger 22 located in the end of handle 12 adjacent to the pawl 18. Plunger 22, mounted eccentrically with respect to the axis of handle 12 in FIG. 3, is driven leftward by means of a spring 11 shown in the cut-out, FIG. 3, and cooperates with a surface 23 on pawl 18, (FIG. 5b). The plunger 22 could be skewed with respect to the axis of handle 12, as shown in FIG. 6, with a protrusion 34 being present to provide additional support with minimum interference with the sides of surface 23, which may also be formed by drilling a clearance hole into the back of pawl 18 rather than milling the flat surface 23 shown in FIG. 5b. In such case, the skewed position of plunger 22 is preferred as it cooperates most readily with the conical shape of the base of the drilled hole (shown more clearly, though without a through-passage, in FIG. 8, detailing the pawl member of the alternate embodiment described subsequently).

If handle 12 were to be rotated 180° from the position shown in FIG. 1 — that is, with plunger 22 below the axis of handle 12 rather than above it as depicted in FIG. 1 — then plunger 22, still urged leftward by spring 11, would cause pawl 18 to rotate clockwise and bring the lower one of the two teeth 15 into engagement with the mating teeth of ratchet 13. For greater strength, as shown in FIG. 4, a duplicate of ratchet 13 may be positioned on the other side of a groove 21 which is present for purposes described subsequently.

Pawl 18 is guided for the above-mentioned oscillation by means of its circular top 26 and a stud 17 seen at the bottom in the elevation views of FIGS. 5a, b, c. These portions of pawl 18 engage mating holes 17a, 26a in head 14, as seen in FIG. 2. The handle 12 is kept in the position to which it has been rotated — for purposes of controlling pawl 18 — by means of two detents 24 mounted at right angles to the axis of handle 12, as seen in FIG. 1, these detents being urged by a spring 27 (shown only partially in the cut-away portion of handle 12 in FIG. 1) into engagement with a pair of holes 29 in head 14.

For economy and ease of assembly, handle 12 is also made to serve the function of holding the entire assembly together. This is achieved, see FIG. 3, by means of an extension of handle 12, i.e., a cylindrical tongue 20 projecting from that end of handle 12 which has plunger 22 mounted in it. Tongue 20 passes through a mating hole 19 in pawl 18 to engage the groove 21 in tool driver 16, as can be seen from FIGS. 5b and 4, respectively. Because of the required oscillation of pawl 18 for reversal of the drive-direction, hole 19 must have its lateral edges 25 appropriately chamfered or elongated as shown in FIGS. 5a and 5c.

Once handle 12 is inserted into head 14 with members 16 and 18 in proper position — that is, assuming the orientation of head 14 shown in FIG. 2, with members 16 and 18 oriented as shown in FIGS. 4 and 5b, the tool driver 16 being held up either manually or by a clamp, in known fashion, during the assembly process — then tongue 20 locks the assembly together, i.e., the parts 16, 18 are positively held in head 14. Tool driver 16 is then free to rotate in head 14 because of a sliding fit between the cylindrical surfaces 31 and 32 on driver 16 and the mating holes 31a and 32a, respectively, but is substantially fixed axially because of the locking action between tongue 20 and groove 21. The opposed orientation of driver 16 and pawl 18 is of importance because it con-

tributes to the strength of the assembly. This is so because an end load applied to either of these members in the direction tending to remove that member from head 14 is opposed by the other member through the action of tongue 20, which has a close fit in groove 21 and in hole 19.

Detents 24, shown projecting through the chamfered holes 29 located 180° apart (see FIG. 1) in head 14, define the angular positions of handle 12 for normal drive and reversed drive, as mentioned previously. Further, they serve to hold the entire assembly together regardless of the handle orientation because of a circumferential groove 28 located within head 14 at right angles to the axis of handle 12. The groove 28, shown in FIG. 2, is of a width to match detents 24 and allows rotation, but no axial movement of the handle, unless the detents 24 are simultaneously depressed to a clearance position for purposes of disassembly, as is obvious.

An alternate embodiment of the invention permitting a thinner cross section for the one-piece body and a greater area of contact between the teeth of the pawl and ratchet members will now be described. FIG. 7 shows an exploded view of the wrench (except the handle) according to the alternate embodiment. The head 35, shown in cross section similar to FIG. 2 for the first embodiment, now has a groove 37 cut in the hole 32a. Groove 37 is of such a depth that it cuts through the wall of the adjacent hole 17a which receives the stud 17 of the double-toothed pawl. In this alternate embodiment, a modified pawl 38 is used, differing from previously-described pawl 18 not only in that it is shorter, as required by the thinner cross section of the head 35, but also because of the presence of a groove 39 on the exterior of stud 17. Groove 39 is identical in width to the groove 37 described above and is so located axially on stud 17 that the two grooves are aligned when pawl 38 is placed in head 35.

The tool-bearing member 36 of the alternate embodiment differs from that of the first embodiment because there is no groove at the midplane of its ratchet teeth 33 (the smaller tool driver 16a shown on the lower end of member 36 does not form part of the invention according to the alternate embodiment, but is included to help relate the views in FIGS. 7 and 9). When tool-bearing member 36 is inserted into its respective opening in head 35, as shown by the corresponding dotted line in FIG. 7, it will move upward until the edge 46 of ratchet 33 abuts against the internal surface 45 of head 35. In this position, the opposite edge 47 of ratchet 33 will clear the groove 37, and by use of appropriate known compression tools, a retainer 40, consisting of a ring known in the art as a "C-ring," may be inserted in groove 39 and allowed to expand to lock it in groove 39 thus preventing removal of tool-bearing member 36 because of the interaction between edge 47 and the ring 40, which has an inner diameter 41 smaller than the diameter of ratchet 33 even with ring 40 expanded. The expanded diameter 42 of ring 40 is large enough to cause ring 40 to penetrate into groove 39 of pawl 38's stud 17, when received in its mating hole 17a. Pawl 38 is thus simultaneously retained in head 35, though still free to rotate as the tool is operated. In this alternate embodiment, the retaining and reversing means are dissociated, and other known reversing means based on slides or levers could be used with a solid handle as part of the one-piece body, but the rotatable type described in connection with the first embodiment is preferred. For this purpose, as shown in FIG. 10, there is used a handle 33 having a protrusion 34 at its end, with spring-driven plunger 22 mounted askew of the handle's axis, but the tongue 20 being absent in comparison with FIG. 6. The pawl 38 with which handle 33 operates, differs from pawl 18 originally described not only because of the presence of the above-mentioned groove 39 on stud 17, but because of the absence of the no-longer needed through-passage 19 and the use of a drilled hole 43 (see FIG. 8) to form the conical surface 44 found most suitable for cooperation with the skewed orientation of plunger 22. As will be evident to those skilled in the art, the above-described embodiments of the invention are subject to various modifications, the invention being applica-

ble to other tools, such as box wrenches, threading die wrenches, etc. The detailed descriptions are therefore given merely by way of illustration and example, with the intention that the spirit and scope of the invention be limited only by the appended claims.
